(57) **CLAIM**

The ornamental design for a keyboard cleaning tool, as shown and described.

DESCRIPTION

FIG. 1 is a perspective view of a keyboard cleaning tool according to my new design;

FIG. 2 is a front view thereof;

FIG. 3 is a bottom view thereof;

FIG. 4 is a rear view thereof;

FIG. 5 is a left-side view thereof, the right-side view being a mirror image thereof; and,

FIG. 6 is a top view thereof.

Features shown in broken lines are only intended to provide environment and form no part of the claimed design.
